UNITED STATES PATENT OFFICE.

CYRUS L. PEMBERTON, OF FAIRMOUNT, INDIANA.

OIL-BURNER.

1,399,986.

Specification of Letters Patent. Patented Dec. 13, 1921.

Application filed May 14, 1921. Serial No. 469,638.

To all whom it may concern:

Be it known that I, CYRUS L. PEMBERTON, a citizen of the United States, residing at Fairmount, in the county of Grant and State 5 of Indiana, have invented certain new and useful Improvements in Oil-Burners, of which the following is a specification.

My invention relates to improvements in oil burners.

10 An important object of the invention is to provide an oil burner adapted to be arranged in the fire box of a coal stove, and to operate therein, without materially altering the construction of the fire box, or its grate.

15 A further object of the invention is to provide a burner of the above mentioned character, having means to thoroughly heat and vaporize the oil, and mix the same with air, whereby complete combustion is obtained.

20 A further object of the invention is to provide a burner of the above mentioned character, having the main vaporizing chamber and sub vaporizing chamber arranged adjacent to and concentric with the burner element, to receive the maximum degree of heat therefrom.

25 A further object of the invention is to provide a burner of the above mentioned character, formed of few and simple parts, and which is cheap to manufacture and reliable in operation.

Other objects and advantages of the invention will be apparent during the course 30 of the following description.

35 In the accompanying drawings, forming a part of this specification, and in which like numerals are employed to designate like parts throughout the same.

Figure 1 is a side elevation of a burner 40 embodying my invention,

Fig. 2 is a plan view of the same, and,

Fig. 3 is a longitudinal section taken on line 3—3 of Fig. 2.

45 In the drawings, wherein for the purpose of illustration is shown a preferred embodiment of my invention, the numeral 5 designates a receptacle or tray, embodying an upstanding flange 6, as shown. The tray 5 is provided with a pair of air inlet openings 7, within its ends, which openings are surrounded by annular upstanding flanges 8, spaced a slight distance therefrom, as shown.

50 The numeral 9 designates an inverted approximately U-shaped air supply conduit, the ends of which are held within the flanges 8, and are in free communication with the

openings 7. The U-shaped conduit 8 is provided centrally thereof with a depending tubular outlet extension or flange 10, discharging downwardly, as shown.

60 The numeral 11 designates a main generating chamber, preferably formed integral with the base of the pan 5, centrally thereof between the openings 7. A supply pipe 12 leads into the bottom of the main generating chamber 11, and is adapted to feed oil or other liquid fuel into the chamber 11. The numeral 13 designates a sub generating chamber, smaller in diameter than the chamber 11, and arranged above and in concentric relation thereto. The sub generating chamber 11 has its lower end secured to a tubular coupling 14, engaging within a screw threaded opening 15, and leading into the main generating chamber 11.

65 The numeral 15 designates a tubular burner element, the lower end of which is screw threaded into an opening 16. The burner element 15 has apertures 17, and a cap 18 closing its top. The depending tubular outlet or flange 10, surrounds the upper end of the tubular burner element 15.

70 In the use of the device, it is placed within the fire box of the stove, such as a coal stove. The pipe 12 is passed through an opening in the grate and connected with the main generating chamber. The spaces between the grates, excepting the spaces beneath the openings 7 are completely filled with asbestos pulp, and hence the circulation of air 75 therethrough is prevented, excepting through the openings 7 and inverted U-shaped conduit 9. The oil passes upwardly through the pipe 12 into the chamber 11 and sub chamber 80 13 and discharges through the apertures 17 of the burner element, at which point it is

85 ignited, the combustion being supported by the air passing downwardly through tubular outlet 10. The flame is directed downwardly, and intense heat is therefore applied to the 90 sub generating chamber 13 and the main generating chamber 11, particularly the top wall thereof. The heat causes the oil in the chambers 11 and 13 to be more or less vaporized, as it passes through the apertures 17, whereby its combustion is rendered more complete, in the presence of the condensing current of air, surrounding the same.

95 It is to be understood that the form of my invention herewith shown and described, is 100 to be taken as a preferred example of the same, and that various changes in the shape,

size, and arrangement of parts may be resorted to without departing from the spirit of my invention or the scope of the subjoined claims.

5 Having thus described my invention, I claim:

1. In an oil burner, a main receptacle having air inlet openings formed in the bottom thereof, an inverted approximately U-shaped 10 air supply conduit having its ends in communication with the inlet openings and provided with a downwardly discharging tubular outlet, a main generating chamber formed upon and arranged beneath the main receptacle and located between said air inlet openings, means to supply oil or the like into the main chamber, a sub generating chamber arranged near and above the main chamber within the main receptacle and having communication therewith, and a tubular burner element connected with the sub generating chamber and surrounded by the tubular air outlet.
2. In an oil burner, a main receptacle having air inlet openings in its bottom, an inverted approximately U-shaped air supply conduit having its ends in communication with said air inlet openings and provided between its ends with a downwardly dis- 25 charging air outlet, a main generating chamber arranged beneath the main receptacle 30

and located between said air inlet openings, the bottom of the main receptacle constituting the top of the main generating chamber, a sub generating chamber disposed within the main receptacle near and above the main generating chamber and having communication therewith, a burner element connected with the sub generating chamber and projecting above the same, and means to supply 35 liquid fuel to the main generating chamber.

3. In an oil burner, a main receptacle having an air inlet opening in its bottom, an air conduit having one end in communication with the air inlet opening and provided with 40 a downwardly discharging outlet, a main generating chamber arranged beneath and cast upon the main receptacle and disposed beneath the said air discharging outlet, means for supplying liquid fuel to the main 45 generating chamber, a sub generating chamber arranged within the main receptacle above and adjacent to the main generating chamber and having communication therewith, and a burner element arranged above 50 the sub generating chamber and connected therewith, the main generating chamber, the sub generating chamber, burner element, and air discharge outlet being all arranged in substantially concentric relation.

In testimony whereof I affix my signature.
CYRUS L. PEMBERTON.
